UNITED STATES PATENT OFFICE.

MERTON A. REYNOLDS, OF AUBURN, MAINE.

SUPPORTING STAND AND CONTROL SWITCH FOR ELECTRIC IR.

Application filed December 22, 1925, Serial No. 77,051. Renewed June 27, 1928.

This invention relates to control devices for electric irons and has for its object the provision of a novel stand upon which the iron may be placed when not in actual use, 5 the stand being provided internally with a control switch whereby current to the iron will be cut off while the iron is resting upon the stand, the switch closing automatically when the iron is removed from the stand 10 so that heating of the iron will be effected while it is in actual use.

An important object of the invention is to provide a stand of this character which is provided with means whereby the heat 15 radiating from the iron resting thereon will be conserved and reflected back to the iron instead of being permitted to become dissipated in the atmosphere, the iron consequently remaining hot for a prolonged 20 period.

Another object of the invention is to provide a stand of this character equipped internally with a novelly constructed switch actuated by the weight of the iron upon the 25 stand, the switch embodying various peculiar structural characteristics whereby there will be a very rapid or quick make and break of the circuit so as to avoid undue sparking and consequent burning away or pitting of 30 the contacts forming part of the switch.

Still another object of the invention is to provide a device of this character in which the conducting cord to the iron or the iron itself may be equipped with a tell-tale lamp 35 which will be energized when current is fed to the iron so as to give a visible indication as to whether or not current is flowing, the tell-tale lamp being of benefit not only for demonstrating purposes but also to indicate 40 a failure of current or a derangement of the switch mechanism.

A minor object of the invention is to provide a device of this character having a base of such construction or form that when the 45 device is placed upon an ironing board or other support it will remain in one position and not slide about as occurs in the use of ordinary types of supports.

With the above and other objects and advantages in view such as simplicity and ease in construction and operation, efficiency and durability in service, and a general improvement of the art, the invention preferably 50 consists in the combination and arrangement of parts and the detail structure to be hereinafter more fully described and

claimed, and illustrated in the accompanying drawings, in which:

Figure 1 is a side elevation of the supporting stand with an electric iron resting 60 thereon, the conducting cord and plug for the iron being equipped with a tell-tale lamp.

Figure 2 is a perspective view of the support with an iron placed diagonally thereon 65 so as to be supported without operating the current cutoff switch.

Figure 3 is a top plan view of the support with a portion broken away.

Figure 4 is a longitudinal section, the 70 switch mechanism being shown in side elevation, this view illustrating the position of the parts when the iron is removed.

Figure 5 is a view quite similar to Figure 4 illustrating how the insulating lining for 75 the top plate rises therewith upon removal of the iron from the stand or support.

Figure 6 is a longitudinal section through a portion of the device and through the entire switch mechanism so as to illustrate 80 the details of construction of the latter.

Figure 7 is a similar view taken along a different plane and showing the switch in circuit breaking position.

Figure 8 is a detail perspective view of the 85 actuating arm of the switch mechanism.

Referring more particularly to the drawings, I have shown the device as comprising a base member 1 which is formed preferably, though not necessarily, as a metal 90 stamping provided with a downturned peripheral bead 2 of such form as to be capable of having more or less of a biting action upon the surface on which it is placed so that the entire support will remain at the 95 desired location and not slip about as is a common fault with most varieties.

Suitably secured upon the top of this base member 1 and preferably toward one end portion thereof, is a box-like casing 3 which 100 in the present instance is represented as provided at its lower or open end with outwardly directed lugs or attaching elements 4 through which pass the securing bolts 5 or the like which operate to mount the casing 105 upon the base. Obviously, any equivalent securing means may be used if preferred for any reason.

Mounted upon the closed top 6 of the casing member 3 and secured thereto by any 110 desired means, such for instance as spot welding, is a tray-like support 7 which

preferably, though not necessarily, of the same general size and shape as the base member 1. In actual practice the base member 1 and the supporting tray member 7 may 5 have a contour corresponding to a greater or less extent to the shape of a conventional electric iron indicated by the letter A.

Located within the tray-like support and normally resting upon the bottom thereof is 10 a sheet 8 of insulating material such as asbestos, this sheet being preferably imperforate and supporting a second sheet 9 which is preferably, though probably not necessarily, provided with a plurality of holes 15 10 here represented as circular in shape. Located also within the tray-like support above the upper sheet 9 of the heat insulating material is a supporting plate 11 constructed preferably of specially treated steel. 20 The supporting tray member 7 is provided with an upstanding peripheral flange 12 which has its upper edge rolled inwardly and downwardly to provide a retaining bead 13 which will operate to prevent the plate 11 from disengagement from the tray-like support. On account of the shape above mentioned, one end of the tray-like support is comparatively wide whereas the other end tapers practically to a point. The wider end 30 or rather the upstanding flange 12 at the wider end is formed with an elongated slot 14 through which the sheets 8 and 9 of asbestos or other material, together with the plate 11, may be inserted into place within the tray-like support. This detail is one relating only to the actual manufacture and assembling of the device.

The casing member 3 contains a switch device indicated generally by the numeral 40 15, and the underside of the top of the casing member 3 is provided with a lining 16 of asbestos or other heat insulating material. While it is conceivable that different types of switch devices might be used, I have 45 disclosed a specific structure which is designed specially for the purpose and which will be of manifest advantage for reasons to be hereinafter pointed out. This switch device comprises an enclosing body 17 of suitable insulating material, such as porcelain or the like, which body is closed at its bottom as shown at 18 and open at its top, the open side or top being secured against the underside of the top of the casing member 50 3 as by means of bolts 19. The entire switch mechanism is mounted within the body 17 and includes a stationarily mounted bracket 20 carrying a transverse pivot pin 21 upon which are pivotally engaged spaced upstanding ears 22 formed at the central portion of an operating arm structure 23 which has one end formed with a seat or socket 24 and its other end bifurcated at 25 to provide spaced curved arms 26.

60 Projecting from opposite sides of the

bracket 20 are trunnions 27 upon which are rockably engaged the arms 28 of a U-shaped member 29 of yoke-like form capable of swinging in opposite directions, the degree of movement being limited by means of stops 30 depending from the bracket member 20. Figure 6 shows one limit of movement while Figure 7 shows the other limit. The operating arm member 23 is provided with spaced depending lug-like extensions 31 provided with notches 32 within which are engaged trunnions 33 projecting from opposite sides of a saddle member 34 of socket-like form slotted for the passage of a guide rod or bar 35 which carries a socket-like abutment member 36 and which has a reduced extension 37 extending through a suitable opening in the bight portion of the U-shaped member 29. A coil spring 38 surrounds the rod or bar member 35 and engages against the saddle member 34 and the abutment member 36. The engagement of the extension 37 within the slot or opening in the bight portion of the U-shaped member 29 is such as to permit relative rocking movement so as not to interfere with the swinging of the U-shaped member in one direction or the other into engagement with the depending stop 30 carried by the bracket. Secured upon and insulated from one arm of the U-shaped member 29 is an elongated movable contact arm 39 having its end portion preferably of forked formation for engagement with stationary contacts 40 and 41 suitably mounted within the body 100 17. The operating arm of the switch has its socket portion 24 at one end receiving and accommodating one end of a coil spring 42 which has its other end seating within a socket 43 at one end of an angular bracket 105 44 secured within the body 17 as clearly indicated in Figures 6 and 7. This spring acts to maintain the operating arm normally in such position that the movable contact 39 will bridge the contacts 40 and 41. 110

The means here shown for throwing the switch into open position comprises a push button 45 slidable through registering holes in the insulating sheets 8 and 9, the bottom portion of the tray-like support 7, the top 115 6 of the casing 3 and the lining 16 therefor. The push button is provided with a depending shank portion 46 engaging upon the top of the curved arm 26 of the operating lever 23, the shank portion being reduced 120 from this point to define an elongated guide 47 which is slidably mounted through a suitable opening in one end portion of the supporting bracket 20. The spring 42 above described has sufficient strength or tension to maintain the operating arm 23 in such position that the push button 45 will be elevated so as to hold the plate 11 in its uppermost position against the stop bead 13 at the 125 top of the supporting tray. 130

In the actual use of the device it is intended that the switch device be interposed in one of the leads or conductors connected with the electric iron so that it will be necessary for the switch to be closed in order that current may be supplied to the iron. Figures 1 and 2 and also 9 and 10 show the iron A as provided with the usual terminals B located within a metal shield C within which 5 is detachably engageable the usual plug D carried by the so-called cord or flexible conductors which supply current to the iron. There is of course no novelty in this feature though it is included for the purpose of illustrating how the electrical connections to the switch are made. The so-called cord of course includes two separate conductors one of which connects directly with the plug E intended to be screwed into an electric 10 light socket, and the other of which has the switch interposed therein.

In the actual operation, it will be seen that under normal circumstances the spring within the switch will act to hold the push 25 button 45 and plate 11 in elevated position, the switch being consequently closed so that current will be fed to the electric iron. At this time the iron will of course be heated as it is used or in case it be set upon the 30 support transversely thereof so as not to depress the plate 11. When the iron is not being used it is intended that it be set upon the plate 11, as shown in Figure 1, whereupon the weight will act to depress the 35 push button 45 and swing the operating arm 23 of the switch device so that the movable arm 39 of the switch will be swung out of engagement with the contacts 40 and 41, thus breaking the circuit so that no current can pass to the iron while it is resting upon the stand. It will be observed that owing to the provision of the peculiarly treated steel plate 11 and the arrangement 40 thereof with respect to the insulating sheets 45 8 and 9 the heat tending to radiate from the lower portion of the iron will be reflected back to the iron instead of being permitted to become dissipated in the atmosphere, the iron consequently remaining hot for a long 50 time. There seems to be some sort of suction effect produced between the plate 11 and the insulating sheets 8 and 9 inasmuch as it has been discovered that after the iron has been resting upon the plate 11 and is 55 then lifted off the insulating sheets will rise with the plate 11, as shown in Figure 5. Regardless of this detail it is quite clear that an actual experiment has proved that the heat is conserved instead of being wasted.

60 Whenever the iron is removed from the support or stand the switch will be automatically returned to circuit closing position so that the iron will be additionally heated.

In Figures 1 and 2 I have illustrated an 65 additional refinement in the way of an

auxiliary device or indicating means here disclosed as consisting of a suitable member 48 preferably mounted on the protective spring or coil F which surrounds the cord or conductors adjacent the plug D. The 70 member 48 carries a suitable socket 49 within which is mounted an incandescent lamp 50 connected in parallel with the heating coil, not shown, of the iron, so that whenever the current is supplied to the iron the tell-tale 75 lamp 50 will be energized and give a visible indication thereof. Conversely, if the current is cut off or if the switch device is out of order, so that current cannot flow, the deenergization of the lamp 50 will indicate 80 the same so that the operator will be apprised of the unnatural conditions. This feature is also of great importance in demonstrating the iron to prospective purchasers as the energization and deenergization 85 of the lamp will disclose the actual conditions which exist.

It is of course to be understood that the use of this tell-tale lamp is optional and it 90 also might be mentioned that the conductor or cord equipped with the plug and the tell-tale lamp might be used in connection with an electric iron irrespective of the use of the stand or support.

From the foregoing description and a 95 study of the drawings, it will be apparent that I have thus provided a simply constructed, inexpensive and highly efficient and durable device for the purpose specified and one which should perform all the functions for which it is intended, and possess unusual durability owing to the comparative fewness of the parts and the particular arrangement and combination thereof. It is 100 really believed that the construction, operation and advantages will be readily apparent to one skilled in the art without further explanation.

While I have shown and described the 105 preferred embodiment of the invention, it should be understood that I reserve the right to make such changes in the form, construction and arrangement of parts as will not depart from the spirit of the invention or the scope of the subjoined claims.

Having thus described the invention, I 110 claim:—

1. An electric iron supporting stand including a base member, a casing mounted thereon, a tray-like support mounted on the casing, a movable plate mounted within said tray-like support, a control switch mounted within said casing and embodying stationary contacts interposed in one of the leads to the 115 electric iron and further including a movable contact arm normally bridging said contacts for making the circuit to the iron continuous, an operating means for the 120 switch including a push button slidably mounted through the top of the casing and 125

130

the bottom of the tray-like supporting member and arranged in engagement beneath said plate whereby the weight of an iron upon the plate will operate to throw the 5 switch into circuit breaking position.

2. An electric iron supporting stand including a base member, a casing mounted thereon, a tray-like support mounted on the casing, a movable plate mounted within said 10 tray-like support, a control switch mounted within said casing and embodying stationary contacts interposed in one of the leads to the electric iron and further including a movable contact arm normally bridging said 15 contacts for making the circuit to the iron continuous, an operating means for the switch including a push button slidably mounted through the top of the casing and the bottom of the tray-like supporting member 20 and arranged in engagement beneath said plate whereby the weight of an iron upon the plate will operate to throw the switch into circuit breaking position, means for preventing disassociation of the plate 25 with respect to the tray-like supporting member, and a plurality of sheets of heat insulating material mounted beneath said plate.

3. An electric iron supporting stand including a base member, a casing mounted thereon, a tray-like support mounted on the casing, a movable plate mounted within said tray-like support, a control switch mounted within said casing and embodying stationary 30 contacts interposed in one of the leads to the electric iron and further including a movable contact arm normally bridging said contacts for making the circuit to the iron continuous, an operating means for the 35 switch including a push button slidably mounted through the top of the casing and

the bottom of the tray-like supporting member and arranged in engagement beneath said plate whereby the weight of an iron upon the plate will operate to throw the 45 switch into circuit breaking position, means for preventing disassociation of the plate with respect to the tray-like supporting member, and a plurality of sheets of heat insulating material mounted beneath said 50 plate, the uppermost of said sheets being provided with a plurality of openings.

4. An electric iron supporting stand including a base member, a casing mounted thereon, a tray-like support mounted on the casing, a movable plate mounted within said tray-like support, a control switch mounted within said casing and embodying stationary contacts interposed in one of the leads to the electric iron and further including a 60 movable contact arm normally bridging said contacts for making the circuit to the iron continuous, an operating means for the switch including a push button slidably mounted through the top of the casing and the bottom of the tray-like supporting member 65 and arranged in engagement beneath said plate whereby the weight of the iron upon the plate will operate to throw the switch into circuit breaking position, means for preventing disassociation of the plate with respect to the tray-like supporting member, a plurality of sheets of heat insulating material mounted beneath said plate, 70 said base member having a downturned peripheral flange for gripping the surface upon which the base is placed to prevent slipping and sliding.

In testimony whereof I affix my signature.

MERTON A. REYNOLDS.
